 corporation

Application January 24, 1928. Serial No. 249,097

55 Claims. (Cl. 164—49)

This invention relates to machines for fabricating long metal stock of various kinds (sheets, rods, tubes, or even fairly thick wires, but including more particularly in the example shown), sheet metal stock which is narrow as compared with its length and in such machines the stock is caused to travel in the direction of its length and is usually subjected to a plurality of operations, frequently including a shearing into equal shorter lengths as in the example.

As is known, finished strips of sheet metal from the rolling mill are in the form of coils of varying widths. This material, before it is ready for use in final fabricating operations, must be straightened and cut to the desired length. The exemplary form of the present invention illustrates this particular phase of such metal working, that is to say, to the straightening and shearing operations.

The machines which have been used to perform these operations conveniently may be considered as included in two types. The first comprises a series of feed and straightening rolls which operate in conjunction with a shear mechanism to feed, align and shear the metal in an intermittent operation. The material is fed through the straightening rolls and passed beyond for a predetermined length. The rolls are then stopped and the shear mechanism operated to cut off the sheet. This method, while insuring a rigid shear, is decidedly disadvantageous. Due to the fact that the operation is an intermittent one, the time required for the shearing step represents a low production rate.

Under the second type are comprehended those machines in which the sheet is fed from the coil to the straightening rolls with a continuous feed, and those are distinguished from the machines of the first type by continuity of operation. The continuous operation is attained by tripping a shearing mechanism and moving it forwardly with the leveled sheet during the cut off and then returning it to its initial position of rest. The complexity of the mechanical movements involved in such a mode of procedure requires designs which are so special as to show the desirability of solving the problem in a third manner as shown herein.

One mechanical embodiment of the invention is shown as an example in the accompanying drawings, of which Fig. 1 is a front elevation of the machine as faced by the operator, showing the stock A, being pulled into the machine from a coil at the left (not shown) to the right by the feeding mechanism indicated by the central showing of two tiers of rollers 10—13, which feed and straighten the stock; Fig. 1 showing the stock A being fed rightward by said rolls to the shearing mechanism indicated by the vertically operating eccentric;

Fig. 2 is a plan wherein the machine as a whole has been moved clockwise ninety degrees from its position in Fig. 1, so that at the top of Fig. 2 are shown the entrance guide-rolls which are at the left in Fig. 1, and so that near the bottom is shown the shearing mechanism which is at the right in Fig. 1; Fig. 2 showing at its right certain driving mechanism which extends back of Fig. 1; 65

Fig. 3 is a rear elevation illustrating the power connections from motor G (at left Fig. 1) to (a) the feeding mechanism indicated by the group of four tiers of circles and to (b) the shearing mechanism indicated by the vertically operating eccentric; 70

Fig. 4 is an elevation (partly in section) of 75 the terminal end or right end of the machine of which the front is shown in Fig. 1; and

Fig. 5 is an elevation of the starting end or left end into which the stock A (Fig. 1) is fed.

Figs. 1 and 3 therefore respectively show the 80 front and rear of the entire machine; Figs. 4 and 5 show its two ends; and Fig. 2 its top. And Figs. 2, 4 and 5 display face views of the parts which lie behind Fig. 1 and extend rearwardly away from the operator, as indicated in each 85 of said Figs. 2, 4 and 5 by the long wabbing or nutating members 27 which operate the rolls of the feeding mechanism.

The exemplary machine comprises shearing mechanism, a source of power straightening mechanism and transmission mechanism operatively coupling the source of power with the straightening and shearing mechanism. 90

The elements of the machine are mounted on a bed pedestal. At one side (Fig. 5) the pedestal 1 is formed as an oil-tight casing 2 which encloses certain transmission mechanism to be described. At the other side the pedestal 1 is formed with the vertical supporting frames 3, the upper ends of which are horizontally flanged as at 4. The flange or T 4 is cut out to present a channel-groove 5 (Fig. 5) for the reception of certain supporting frame members of the straightening mechanism to be described. An electric motor G used for the source of power may have its casing mounted on a portion 6 of bed plate 1, Figs. 1 and 3 by means of a slot or other suitable connection and adjusted longitudinally by the screw 7. The stock A is fed from left to right, Fig. 1. The machine pedestal 1 also preferably is provided (right, Fig. 1) with a horizontal extension 8 integral as shown, which serves as a table to receive the cut pieces of stock. 100

Before being sheared near the right, Fig. 1, the stock is straightened, and the mechanism for that, termed the roll-stand, is shown in Figs. 1, 2 and 5 especially Fig. 1. It comprises an upper series of six horizontal rolls 10, 12 and a lower series of five rolls (11 and 13). The rolls in each 115

- series are horizontally alined. The rolls 12, 13 at left and right ends of the two series act as pinch or feed rolls. The three lower straightening rolls 11 are spaced from and staggered relative to the four upper straightening rolls 10. The straightening rolls are spaced from one another as distinguished from the stock-pinching feed-rolls 12, 13; but they are positively driven like the feed-rolls as shown.
- 10 Spaced upper and lower guide rolls 14, Fig. 1, to receive the stock A upon its first entrance to the machine and guide it to the above rolls are rotatably mounted in a bracket 15 rigidly secured to the machine frame. Stock A is assumed to be a sheet in edge-view in Fig. 1. The upper face of this bracket is formed with a transverse T-slots 15'. Mounted on the upper face of the bracket are the stock-positioning guides 16. These are centrally apertured to receive a bolt and nut 16', Fig. 1. The head of the bolt fits the slot and by the adjustment of the nut (Fig. 2), the guides 16 may be moved laterally to any desired position and thus serve to guide long sheet stock of different widths.
- 15 Mounted on the vertical frames 3 of the machine-bed, Fig. 5, and connected thereto for sliding movement are vertical roll-stand members or supports 17-18 for the above horizontal rolls. The lower ends of these vertical roll-supports (Fig. 5) are provided with integral lateral extensions 17'-18' respectively. The bottoms of these roll supports 17-18 rest in the channels 5 of the side frames 3 of bed 1. Their width at the bottom provides a wide and solid bearing. Their length from left to right, Fig. 1, is supported to receive all the above rolls, save the guide-rolls 14. These roll-supports are reciprocated left and right, Fig. 1, in the direction of feed of stock A. Suitable bearing rolls or other means to prevent sliding friction of parts 17 and 18 may be incorporated in channels 5. The bracket 15 extends across and is secured to the roll supports 17 and 18 (Figs. 1 and 2). A second bracket 19 is positioned below the lower series of rolls 13, 11 and rigidly secured to roll supports 17 and 18. The members 15, 17, 18 and 19 thus form a rigid housing or support which carries the straightening rolls 10-11 and the feeding or pinch rolls 12, 12. All this with the roll adjusting means described below, constitutes the roll-stand thru which the stock A, Fig. 1, is fed from left to right to the shearing mechanism later described.
- 20 The lower straightening (and feeding) rolls 11 and the lower pinch-rolls (feed-rolls) 13 are journaled in roll supports 17, 18. The rolls of the upper horizontal series however are adjustable in a vertical plane so as to accommodate different thicknesses of long stock and to vary the pressure exerted on the stock passing thru the rolls. To accomplish this adjustment, the four upper straightening and feeding rolls 10 are journaled in separate journal boxes 20. These boxes 20 are connected adjustably to the roll-support 17-18, but are rigid with respect thereto for any given adjustment, as will appear. The ends of the upper feed or pinch rolls 12 are journaled in the separate journal boxes 21. These rolls 12 are mounted resiliently with respect to roll-support 17-18 via springs 21', Fig. 1.
- 25 The journal boxes 20 are directly connected to adjusting screws 22 in any suitable manner. The rolls 12, however, are connected to their respective adjusting screws and hence to roll-support 17-18. This is effected by interposing a helical
- 30 spring 21' between boxes 21 and associated adjusting screws 22.
- 35 Mechanism as below is provided to insure adjustment of the several rolls. Roll support caps 23-24, extending between the upper portions of roll-supports 17-18. These caps are integrally bored to provide journals for the adjusting screws 22 (Fig. 1). The upper ends of screws 22 are squared to receive a crank handle wrench (not shown) to effect the desired adjustment of the rolls.
- 40 In practical operation it is desirable to provide for equal adjustment of the two ends of each of the straightening rolls. When the machine is first assembled, the lower straightening and feeding rolls 11 are set accurately in a horizontal plane. To maintain the parallelism of the upper end lower rolls during adjustment, the several adjusting screws 22, which are journaled in the cap member 23, are positively connected to the respectively alined adjusting screws 22 of cap 24. In the preferred (and illustrated) construction, this connection is obtained by keying a worm-gear 25 (Figs. 1 and 2) on each of the adjusting screws 22. The gears are held from longitudinal displacement with respect to the adjustment screws 22 by means of the lock nuts 25'.
- 45 The roll support caps 23-and-24 are formed (Fig. 2) with vertical flanges 23'-24'. These flanges, in addition to strengthening the structure generally, serve specifically as a mounting means for shafts 26 for worm-gears 25. These shafts extend across the tops of the rolls and are journaled intermediate their ends in flanges 23'-24'. To prevent longitudinal displacement, 100 shaft 26 is provided with collars 26', which are disposed closely adjacent the faces of the vertical flanges 23'-24'. The shafts 26 (Fig. 2) extend thru and project beyond said flanges 23'-24', and the projecting portions of the 105 shafts are provided with worms meshing with the worm gears 25 as shown. At each end the worm shafts 26 are squared for the reception of a crank handle wrench for adjusting.
- 50 The operation of the adjustment members is 110 as follows. When it is desired to adjust the spaced straightening and feeding rolls 11 or pinch-feed rolls 12 either for stock A of different gages or to vary the pressure or straightening "set" exerted on the stock as sheet A, that may be 115 done by manipulation of the worm shafts 26 with a suitable crank handle wrench. On rotation of a worm shaft 26 the gears 25 connected to the ends of adjusting screws 22 will be rotated thru equal arcs and the associated journal boxes 120 20 or 21 will be raised or lowered an equal distance. In this manner the two feed rolls 12 are maintained in parallel relation in the same horizontal plane with each other and with the four straightening rolls 11, whatever may be the extent of vertical adjustment by turning shafts 26. Each upper roll 11 may be adjusted vertically from any one of four points; i. e., the worm shaft 26 may be rotated directly from either end or it may be rotated via gears 25, by turning either 125 of the adjusting screws 22. Each of all these upper rolls is adjustable individually. An advantage of this construction is that, if desired, the pressure (or straightening "set") exerted by the rolls 10-11 on the sheet may be graduated 130 so as to insure convenient operation and produce a perfectly straightened sheet A.
- 55 The straightening and feeding mechanism above described is connected to a transmission 135 mechanism which drives the several rolls in the

- proper directions and permits the movement of the roll support in a manner to be described. The rolls 10, 11, 12 and 13 are driven (Fig. 2) by wabblers 27. One set of ends of 27 are connected 5 via universal joints 27' to the respective rolls to be rotated. The other set of ends of 27 is connected via similar joints to the driving means including universal joints 27'. The connections of 27 are such that during the feeding to be described of stock A (Fig. 1) they drive the upper rolls 10 and 12 in a counterclockwise direction and the lower rolls 11 and 13 in a clockwise direction. These directions of rotation, however, may be reversed for other purposes, as will appear.
- 15 At the drive end wabblers 27 (right Fig. 2) are connected to gear shafts 28 journaled in the gear box 29, Fig. 4, right, and Fig. 5 left. Journaled within the gear box 29 are a number of shafts shown on which are fixed the spur gears 30, Figs. 20 3-4. There are four horizontal tiers of gears 30 (Fig. 3), the gears of each tier meshing with those of the adjacent tier or tiers. The shafts of the two intermediate tiers are connected to wabblers 27, Fig. 4. The drive for spur gears 30 25 is from the spur gear 31, Figs. 2 and 4. Shaft 28' of drive gear 31 extends (Fig. 5) thru gear box 29 to the wabbler 27 of the lower rear pinch-roll 13. Those of gears 30 which are connected to the row of wabbler-shafts 28 (six in number) 30 are immediately connected by means of the upper tier of spur gears 30. These are placed in staggered relation to the spur gears of the wabbler shafts 28. Similarly the gears 30 connected to the lower group of wabbler shafts 28 and 28' 35 (total five in number) are connected to each other via the lowest row of gears 30.
- If the drive gear 31 is driven in a clockwise direction, (Fig. 3) its connected shaft 28' and the lower pinch rolls 13 will rotate in the clockwise direction to act on stock A, Fig. 1. Since the gear 40 30 carried by this shaft 28' meshes directly with the spur gear 30 of the wabbler 27 which is connected to the upper pinch roll 12, this latter will be driven in a counter clockwise direction, Fig. 1.
- 45 From here the gear train Fig. 3 proceeds to the upper of idler spur gear 30 which is driven in a clockwise direction. Since this is in mesh with the companion gear 30 connected to the shaft 28 of wabbler 27 for roll 10, the latter consequently will be rotated in a counter-clockwise direction as desired to act on stock A, Fig. 1. In this manner the gear train operates to drive the upper pinch-feed rolls 12 and the upper straightening and feed rolls 10 in one direction, and all 50 the lower cooperating rolls in the opposite direction, so that each roll 10-11 aids in straightening and all the rolls cooperate in feeding stock A, longitudinally left to right (Fig. 1).
- The stock A is fed continuously thru all the 55 rolls. This feeding and straightening is accomplished both by moving the stock thru the rolls (left to right, Fig. 1) and by moving the rolls longitudinally with respect to the stock. In the present invention the continuity of feeding operation during the shearing step at the right of Fig. 1, to be described is obtained by the latter expedient, that is, by displacing the rolls longitudinally of the metal strip. This is done simultaneously with the shearing operation.
- 70 Gear 31 (which drives wabblers 27) is driven by pinion gear 32 (Fig. 4) keyed upon the end of a drive-shaft 33, journaled in the bearings B formed on transmission housing 34. A jack-shaft 35 is journaled in bearings F and spaced below drive shaft 33 (Fig. 4, right and Fig. 3, left). A double- 75
- end friction clutch C is mounted on drive shaft 33 intermediate bearings B. This clutch is adapted to connect drive shaft 33 to jack shaft 35 so as to rotate 33 in either direction. To accomplish this a spur gear 36 is keyed to one of the members of clutch C and 36 meshes with a gear 37 fixed to jack shaft 35. A chain sprocket wheel 38 is fixed to the quill E (loose on shaft 33) of clutch C. Wheel 38 is connected by chain-belt D to a chain sprocket 38a keyed to jack shaft 35. Clutch C may be operated manually by an extension (not shown) to a lever 39 (Fig. 3). This lever is attached to the rock shaft 40 and at the other end is secured the clutch yoke 41 Fig. 5. The yoke 41 may be operated to couple the jack shaft 35 to the shaft 33 either through the intermeshed gears 36 and 37 or by the chains D connecting sprockets 38 and 38a. If jack shaft 35 is rotating in the counter clockwise direction and it is coupled by the gears 36 and 37 to drive shaft 33, then 33 will rotate clockwise; but if shaft 33 is coupled through the chain belt drive 38-D-38a, then it (33) will rotate in the same sense as jack shaft 35, i. e., in the counter-clockwise direction.
- 80 85 90 95 100 105 110 115 120 125 130 135 140 145 150
- Jack shaft 35 projects (rightward Fig. 5) through and beyond the transmission housing 34 wherein there is keyed on it a chain sprocket wheel 42. A link-belt chain H passes over 42 and a sprocket wheel 42 is fixed on the shaft 105 of main driver G, Fig. 1. (Other specific forms of driving means, such as cooperating spur gears, etc., may be used in place of this belt drive). Motor G, through the connections 42a-H-42, rotates jack shaft 35, and 35 imparts movement 110 to drive shaft 33 in clockwise or counter clockwise direction, depending on the position of engagement of clutch C by yoke 41. Since shaft 33 is connected positively to wabblers 27 (Fig. 4) which rotate the feed-rolls, therefore motor G 115 is the source of power for said rolls.
- Motor G also drives the shear mechanism in synchronization with the rolls. A bull pinion gear 43 (Figs. 4-5) is keyed to jack shaft 35 and meshes with bull gear 44 mounted on the 120 shaft 46 via clutch 45. Shaft 46 (Fig. 4) is journaled in frames 3 in bearings J and extends beyond these bearings at each side of 3. Bull gear 44 is rigidly mounted on the hub 45a of clutch driver 45 for rotation therewith. This 125 hub is mounted loosely on shaft 46 and idles thereon until it is connected thereto in a manner to appear presently.
- A spur gear 47, (Figs. 4 and 5) is keyed on shaft 46. This gear 47 meshes with a corresponding spur gear 48, which is keyed to a cam shaft 49, journaled in bearings K in frames 3. Fixed to the cam shaft 49 are a plurality of cams 50. 130
- A plurality of cam thrust rollers 51 are mounted on the terminal of bracket 19. These rollers are 135 kept in contact with the cams 50 in a manner to be described more fully hereinafter. On rotation of cam shaft 49, cams 50 will thrust against the cam follower rollers 51, and (through the connection of bracket 19 to the roll-stand) will cause the latter to be moved longitudinally 140 (to the left in Fig. 1).
- Two shear-eccentrics 52 (left, Fig. 4) are keyed on the ends of bull shaft 46. These eccentrics are so positioned as to simulate the impact of a hammer blow, that is, the greatest degree of kinetic energy of the moving parts is utilized on the cutting down stroke, i. e. cutting takes place during the third quarter of eccentric rotation. These eccentrics 52 positively actuate 145 150

the shear gate 53. The upper part of 53 is provided with integral elongated bearings 53' (Fig. 4) in which is journaled a dead shaft 54. Near the outer ends of 54 are pivoted the terminals 55 for connecting rods 56 from the eccentrics; 55 being held on 54 by collars 55'. The lower extending tubular portion of terminals 55 are threaded internally to receive the upper ends of the connecting rods 56, and these connections are locked 10 by lock nuts 57. Each connecting rod 56 is in similar threaded and locked relation to integral portions 58 of the two eccentrics 52.

Shear gate 53 (Fig. 4) slidably engages vertical guide-ways 59, secured to vertical supports 60, which at their lower ends are supported on frame 3. (Gate 53 may be formed with V-shaped extensions which fit into correspondingly shaped grooves in ways 59.) Ways 59 preferably are composed of bronze or some such durable bearing 20 metal. Supports 60 are reinforced and strengthened by means of a supporting strut 61, (Figs. 1 and 3) preferably of T-shaped cross-section, which is secured to the top of 60.

Shear gate or carrier 53 carries the inclined 25 cutting blade 63 and a holding mechanism 62, 62' for the sheet metal stock A. The shear carrier 53, Figs. 1, 5 is formed with two projecting ledges 53a which are bored to form vertically aligned apertures into which are fitted the rods 62. At 30 their lower ends these rods are provided with the blocks 62', which are positioned near the cutting blade 63. Encircling the rods 62, intermediate their ends, are the helical compression springs 64. At one end, these springs abut the lower face 35 of the upper ledge 53a and at the other end they abut the collars 64', Fig. 1, which are fixed (as by a pin) to the rods 62. Upon downward movement of carrier 53 holding blocks 62' first will engage the straightened stock. As the downward 40 movement of the carrier 53 continues, the springs 64 will be compressed and will exert a resilient holding force on the stock and prevent its further longitudinal movement because the stock is held firmly between the blocks 62' and the bracket 45 65, Fig. 1, which supports the stationary shear-blade 66. Further downward movement of the carrier 53 will carry the cutting edge of the movable blade 63 past the stationary shear blade 66 and shear off the now stationary metal strip. 50 When the shear carrier 53 is raised, in any manner, it will carry the rods 62 upwardly and release the blocks 62' from their frictional engagement with the stock in preparation for its next rapid feeding movement between blades 63, 66 55 due to the cooperative bodily and rotary motions of the feed-rolls.

Thus far it will be seen that by means of a single source of power, such as the motor G, the leveling and pinch rolls may be driven through 60 the transmission mechanism comprising the jack shaft 35, clutch shaft 33, gear train 32, 31 and 30, and universally jointed wabblers 27. The shear mechanism and leveling roll support also are actuated by the same motor G by the shaft 46 coupled to the bull gear 44.

In accordance with the principles of this invention, the stock A is fed continuously to the leveling mechanism and the shear mechanism is operated intermittently, that is to say, at predetermined intervals. The one-revolution clutch mechanism, shown in Fig. 4, affords a means of accomplishing these results. As shown, this comprises a cup or driver 45 having a reduced and extended collar or hub 45a, on which is rigidly mounted the bull gear 44. The driver 45 over-

hangs the main clutch body 67, and is lined with a hardened steel liner 68. The clutch body 67 is attached to the bull shaft 46 by a feather key 69. At the end adjacent the driver 45 the clutch body member 67 is enlarged and the locking rolls 70 are interposed being mounted in suitable recesses and normally free from engaging with liner 68 of driver 45. The locking rolls 70 are moved into and out of their cooperating recesses in the clutch body 67 by the roll basket 71 which encircles the reduced tubular portion of member 67. The basket is retained in position on the member 67 by the end plate 72, which is held by the threaded nut 73 adjustably rigid on the reduced end of shaft 46. A coiled tension spring 74 encircles the basket 71, being locked at one end to plate 72 (see Fig. 2) and at the other end to the stop nose or lug 71a integrally formed with the basket. The basket 71 is at all times under clockwise tension by means of the coil spring 74. 80 85 90 95

At the other end of the shaft 46 there is keyed, or otherwise suitably fastened, a retarding brake drum 75. Encircling the brake drum is a flexible band 76, lined with leather, or other suitable friction material. The band is anchored to the side 100 frame 3 by the anchor stud 78. The friction band is adjusted by means of bolt 77 which passes through the terminals of the friction band. The purpose of the brake is to stop the shaft 46 in the same position each time the one revolution clutch 105 is disengaged and prevent energy of moving parts from carrying shaft 46 past its zero position. In the example, the brake is engaged constantly.

Means are provided to regulate the length of stock feed between each cut in the form of a well-known type of variable speed transmission as shown as and known as the "Reeves transmission". This is designated generally on the drawings by the letter "O" and since the transmission itself is well known it will be described here only 110 in its relation to the cooperating elements of the present combination. As shown in Figs. 2 and 3, a drive chain 79, which passes over the sprocket wheel 80 keyed to the gear shaft 28a extending from one of the shafts 28, also passes over the 115 sprocket wheel 200. This wheel 200 is keyed to the constant speed shaft 81, Fig. 3, of the variable speed transmission "O". The variable speed shaft of the Reeves transmission is indicated at 120 82, Figs. 2 and 3. Since the shaft 28a is connected (through the spur gears 30) to the pinion 32, the variable speed transmission is itself driven by the motor G. The variable speed transmission is provided with a lever as shown which is operated to adjust the speed of the output or variable 125 speed shaft 82 (Figs. 2 and 4). This controls the uniform length of the sheared sub-length of stock as now will be described. 130 135 140 145 150

Mounted on a projecting end of the variable speed shaft 82 is a circular cam disk 83, Figs. 1-3, 135 which is formed with a cam 83a, Fig. 2. Mounted on the gear box 29, Figs. 1-2, as by the pivot 84, Fig. 2, is a bell crank lever 85. One end of this Figs. 2-3 extends towards and terminates adjacent to the cam disk 83 on shaft 82. On this end of 85 is pivoted, as by a stud 86, a cam thrust roller 87, Fig. 2. Pivoted secured, Fig. 2 to the short arm of the bell crank lever 85, by means of a stud 88, is a plunger rod 89. Enclosing the rod 89 is a compression spring 90. The spring abuts a shoulder on the rod 89 at one end, and on the guiding bracket 91' on the other end. As is shown in Fig. 2, the plunger 90 is adapted to move into a casing P which houses an electrical switch (not shown). Once in each revolution the cam 145 150

83a abuts the cam roller 87, causing pivotal movement of the bell crank lever 85 about its pivot 84, compressing the spring 90, thereby forcing the plunger 89 within the housing P and actuating 5 the switch therein. When the cam has passed the roller the compressed spring forces the plunger 89 outwardly and pivots the bell crank 85 in the reverse direction, thereby returning the plunger 89 to an operative position. The rate of revolution 10 of cam 83a on wheel 83 depends on the above adjustment of the variable speed transmission.

The actuating of the electrical switch in housing P effects operation of the one-revolution clutch 67, Fig. 4, and hence the roll-stand and the 15 shear mechanism intermittently driven by said clutch. The closing of the switch in housing P completes an electrical circuit and at once energizes the magnet coils of the solenoid or electromagnet "Q" (Figs. 3 and 4). The solenoid is 20 provided with the usual plunger 91. The plunger is linked to a lever 92 by means of the connecting pin 93. The other end of lever 92 is fixed to the stub shaft 94 (Fig. 2) to the other end of which is keyed a lever 95. At its lower end, the lever 95 25 carries a stud 96 which is pivoted to the longitudinally displaceable clutch stop plunger 97. Abutting the end of the lever 95 is a coiled spring 98. The clutch stop plunger 97, stud 96 and spring 98 fit within a suitably designed casing 99. As 30 shown in Fig. 3, an adjusting screw 99' regulates the tension of spring 98.

When the switch in housing P is closed by the plunger 89, the solenoid Q is energized and by means of the described linkage the solenoid with 35 draws the plunger 97 from its engagement with the stop nose 71a of the one-revolution clutch 67, 45, Fig. 4. The roll basket 71 thus is free to be rotated in the clockwise direction by the force exerted by the tensioned spring 74. Such rotation 40 moves the locking roll's 70 circumferentially and into locking engagement between the hardened steel liner 68 and the inclined surfaces N (Fig. 3). This locks the clutch body 67 to the driver 45 of the clutch normally rotated by bull 45 gear 44.

The shaft 46 will now operate through a cycle of one revolution during which it operates the roll-stand and the shearing mechanism. At the 50 end of said cycle the clutch stop nose 71a will abut the plunger 97. This causes the roll basket 71 to disengage the clutch-locking rolls 70 from their locking or driving positions. The shaft 46 now being disengaged from the positive drive of the locking rolls and gear 44, will immediately 55 come to rest, since it is frictionally retarded by the brake band 76.

As the shaft 46 makes its one-revolution cycle, the positive connection afforded by the eccentricities 52 and connecting rods 57 causes the movable shear blade 63 to start from its position of rest (mid-up position as shown in Fig. 1) and to rise to the top of the throw of the eccentric and then to descend 180°, shearing the stock A on the third quarter of the eccentric revolution 65 by what is, in effect, a hammer blow of the blade (and the associated masses) on the stock to be sheared. The fourth quadrant of the cyclic eccentric movement raises the shear blade 90° to the mid-up position of rest, allowing stock A to 70 be freely fed beneath the blade until the cam 83a again acts to trip the clutch and connect bull gear 44 to the shearing mechanism for the next cut-off. On the down stroke of the shear 63 the blocks 62' engage and hold the stock A 75 immovable, while the shearing edges of the two

shear blades 63, 66 pass each other. This mode of operation affords a solid shear and insures a clean cut-off of the metal.

During the operation of the shear the roll-stand carrying the feeding and straightening rolls 10-13 is receded (moved leftward, Fig. 1) from the shear 63, 66 so as to provide for the continuous straightening and feeding of the stock A while allowing a shear fixed in the direction of stock travel. The operation of this phase will be understood from the description of the parts given hereinbefore. As the bull gear 44 rotates to actuate the shear mechanism, it also drives the cam shaft 49 by way of the meshed gears 47 and 48 keyed to 46 and 49 respectively. This imparts clockwise rotative movement to the cam shaft 49 (as viewed in Fig. 1). The revolution of cam shaft 49 carries the cams 50 through a dwell of 180°. Thereafter the cam acts on the cam rollers 51 and, through the connection to the leveling support (roll housing) afforded by the bracket 19, forces the roll-stand carrying rolls 10-13 to recede at a rate of speed equal to the feeding out of the stock between the rolls rightwardly, Fig. 1.

At the end of said recession of the roll-stand carrying rolls 10-13 it is automatically returned to position by the apparatus shown in Fig. 1. As is there illustrated, a counter-balance weight 100 is attached to the chain or cable 101. This chain 105 or cable is secured to the cam bracket by a clevis 102 and passes over a sheave 103 rotatably mounted on the transverse shaft 104.

Since it is the variable speed transmission O which determines the length of the sub-lengths 110 of stock to be cut off, this may be readily adjusted to cut the material to required lengths without varying the speed of the rolls 10-13 the effect of the adjustment being to vary the rate of shaft 82 and the cam 83 as revolved by 82.

While an electrical circuit embodying a solenoid has been illustrated as a functioning part of the trip mechanism, this may be replaced by a mechanical linkage to accomplish the same result to trip the one revolution clutch 67, 45.

There are times when the rolling mills are called upon to furnish strip stock (particularly that of non-ferrous metals) made up in coils and without regard to length. In such cases the operations of straightening and cutting to 125 a predetermined length might not be needed but nevertheless is useful to cut out flaws, etc. from the strips. This operation has been performed by the manufacturer on what is termed the "inspection bench". This inspection and 130 cutting out of defective parts may be accomplished by the machine hereof, as follows. In such an operation the stock is passed through the feed-rolls as hereinbefore described but at a more rapid rate and without, of course, automatically operating the shear 63, 66, but only when desired to cut out a bad spot. As the stock moves through the machine quite rapidly, a bad spot usually passes some distance beyond the shear 63 (rightwardly, Fig. 1) before it is perceived by the operator of the machine. In such circumstances it is desirable to reverse the feed rolls to feed the imperfect section of stock back (leftward, Fig. 1) into position under the shear 66 to be cut off. This may readily be accomplished by manipulation of the hand lever 39, Fig. 1, operating reversing clutch C, Fig. 5. In normal operation for straightening and shearing the drive from the motor to the straightening rolls includes the spur gears 36 and 37.

This causes the upper rolls (Fig. 1) to rotate counter clockwise and the lower rolls clockwise. If now the lever 39 is thrown to the reverse position, the clutch C will be engaged on that side 5 which is driven by the chain belt D. This clutch engagement causes a reverse direction of rotation of shaft 33 and consequently will change the direction of rotation of the upper and lower rolls so that the stock will be fed back (left, Fig. 1) thru the rolls. This movement may be continued until the desired portion of the strip is under 10 the shear 66, at which time the tripping of the other clutch 67, 45 to operate the shear mechanism may be operated as above by manually closing the switch in housing P, Figs. 3-4, to 15 energize electromagnet Q. During such an inspection operation the electric circuit is opened at the switch in P in order to preclude operation of the solenoid Q. Likewise the roll-stand carrying pinch feed rolls 12, 13 is locked in its maximum receded position (to left, Fig. 1) with the 20 upper tier of straightening rolls 10 raised clear of the stock being inspected and fed by rolls 12, 13 over the top of the lower tier of rolls 10. In this position of the parts there is substantial 25 longitudinal space between the roll-stand and shear mechanism which permits an additional view of the material passing through.

The operation of the rolls for continuously feeding the long metal stock rectilinearly lengthwise and for simultaneously straightening it and simultaneously but intermittently shearing it into equal sub-lengths, but intermittently stopping the lengthwise rectilinear movement of the stock thru the shearing mechanism, while continuing the feeding and straightening operation, 30 is as follows. The object of this operation is to increase the rate of production of machines of this general type, particularly the well-known machines supplied with coils of long metal stock which are to be sheared into equal sub-lengths. In order that the sheared lengths shall be equal 35 it is necessary to do two things, first to straighten the stock by removing the metal set of its coil-curvature and establishing a new metal set in a straight condition and second, to operate the shearing mechanism at times when equal lengths of the straightened stock have been fed between and beyond the shearing tools. In the present machine these two things are done without discontinuing the straightening and accompanying feeding operation and without moving the shearing mechanism along the length of the stock, and by moving the long stock exclusively 40 rectilinearly to and between the shearing tools. The stock is substantially rigid lengthwise so 45 that as it passes between the shearing tools and lies beyond them for shearing it must be straight, for if displaced from its straight lengthwise feed to and beyond the shearing mechanism it would 50 be sheared into portions having various curvatures and lengths, unless some means were provided somewhere for taking out the coil-curvature before shearing. In other words, here, where the shearing means is not moved along the line of lengthwise stock-feed, it is necessary to provide other means than lateral stock-displacement out of the line of rectilinear lengthwise stock-feed, to keep the stock from lengthwise movement while the shearing tools are operating on it across the straight path of lengthwise stock-feed. The object of the operation 55 of the machine shown is to provide for lack of relative lengthwise movement of the longitudinally fixed shearing tools 63, 66 at the time they

cross the straight path of lengthwise stock-feed, but yet prevent loss of time otherwise consequent upon stopping stock-movement against the shearing tools, by continuously rotating the straightening and feeding rolls, the former participating in the feeding operation.

This is done in the present invention, and in connection with exclusively rectilinear lengthwise stock-feed, by means of power connections which rotate the feed-rolls at a constant rate as by the wabblers 27, in combination with the separate power-reciprocation of the sliding roll-stand in the line of stock-feed over very short distances (six inches in the machine shown), this rectilinear reciprocation of the roll-stand and the simultaneous operation of the vertically movable inclined shear-blade 63 being effected only after long periods of rest of the roll-stand and shearing tool 63 during which the greater portions of the stock-lengths to be sheared off successively are straightened and fed by the same rolls, the sheared-off straight sub-lengths having substantial length up to fifteen or twenty feet or more as commonly produced heretofore in machines of the general straightening and shearing type. A heretofore existing problem has been how to accomplish the above object, with exclusively rectilinear lengthwise stock-movement, without requiring impracticably long rectilinear reciprocations of the feed-rolls for 105 the purpose of allowing sufficient time for the roll-stand to have its rate of reciprocation accelerated to a practically high rate of rotation of the feed-rolls mounted on the roll-stand; for the movement of the stock relative to the shearing tools cannot be stopped until the rate of movement of the roll-stand away from the shearing-tools is as high as the rate of the stock caused by the continuous rotation of the feed-rolls at uniform rate. This problem has been 110 solved in the present invention by the provision of the mechanism which operates the roll-stand and shearing tool 63 in coordinated time relation and in such manner that within a practically short length of sliding reciprocation of the roll-stand its rate can be brought up from a position 115 of rest to a rate equaling a practicably high rate of rotation of the straightening rolls which feed the stock thru the roll-stand, in order not only that the desired high rate of roll-rotation may 120 be preserved but that in addition the production time actually can be saved by compensating for time otherwise lost by interruption of movement 125 of the stock lengthwise during the shearing operation.

In this machine the mechanism which permits all the above to be effected, without any displacement of any portion of the stock out of its straight lengthwise path from its coil to the shearing mechanism, and with exclusively rectilinear movement of the stock lengthwise, includes the roll-locking clutch N which is normally disengaged, and the large, heavy gear 44 which is continuously rotated so as to act as a fly-wheel in which energy normally is stored which is utilized 140 in the intermittent operations of shearing tool 63 and of the roll-stand; the times of intermittent engagements of the elements of clutch N being controlled by some suitable mechanism such as that shown for the purpose of operating shear-blade 63 and the roll-stand at times which produce equal straightened sheared lengths of the particular long stock being treated which is substantially rigid lengthwise.

The fly-wheel action of bull-gear 44 not only 145

promptly starts the normally stationary shearing-blade 63 and its carriers or shear-gate in operation and sustains its shearing load, but at the same time it also overcomes the inertia 5 of the normally stationary and yet heavier roll-stand and quickly brings up the rate of the latter to that of the lengthwise feeding movement of the stock due to the rotation of the straightening rolls which move the stock thru the roll-stand so that within a practicable length of movement of the sliding roll-stand (permissively even longer than the six inches of the machine shown), there is a stoppage of the movement of the stock 10 relative to the shearing tools for a sufficient time for the shearing cut without starting the slide of the roll-stand before the start of movement 15 of shearing tool 63. The braking mechanism also is important in checking the operations of roll-stand and shear which are started by clutch N and fly-wheel gear 44 which in turn are started by the stock-length controlling mechanism shown.

Thus, altho the power-rotation of the various rolls 10-13 is continuous at a uniform rate by way of wabblers 27, (independent of the clutch N which intermittently operates shearing-tool 63 and the roll-stand), and altho the movement of the stock rectilinearly lengthwise relative to the shearing-tools is interrupted intermittently 20 while the straightening and pinch-rolls are feeding the longitudinally rigid stock lengthwise rectilinearly in a direction thru the roll-stand toward the shearing-tools during the continuous uniform rotation of the rolls, yet the return sliding movement of the roll-stand rectilinearly toward the shearing-tools carrying with it the rolls and also the stock continuously moved by the rolls, relative to the roll-stand, is such, as will be seen, as to compensate for the time otherwise lost, of lengthwise movement of the stock relative to the shearing-tools, thereby accomplishing the desired object of increasing the time-productivity of the machine. Thus, this operation permits an increase of about one foot of stock fed for each 25 cut by the shear; so that, assuming about ten cuts per minute, there is an increased output from the machine of about ten feet per minute, which is of an increased output per day of four or five thousand feet per machine. The cycle is as follows, starting from a position of the roll-support or roll-stand adjacent the shear 63, 66 as the shear blade 63 is about to be operated, both blade 63 and the roll-stand being started in operation and operated by the clutch N and fly-wheel gear 44. The roll-stand (carrying the rolls 30 10-13) begins to recede from the shear (leftward, Fig. 1) and from the forward end of the longitudinally rigid stock A, (right, Fig. 1), this recession of the roll-stand being (at the instant of shearing) at the same rate as the emergence of the stock A from the rolls prior to the gripping of the forward end of the stock. (The acceleration of the roll-stand by fly-wheel gear 44 is under control of the cams 50.) Thus the rolls 10-13 and the forward end of stock A continue their separation from one another at the same rate after the movement of the stock to the shear has been stopped as before it was stopped; but altho the stock now continues to be fed out of the rolls, (rightwardly, Fig. 1) yet it no longer is moved toward the horizontally fixed shear, because of the leftward movement of the roll-stand at the same rate (at the instant of shearing) as the feed of the stock thru the roll-stand. Thus the rolls continue their feed-

ing and straightening action on the stock during this recession of the roll-stand leftwardly from the shear. At the instant of shearing there is no change in the relation of any of the stock to the shear. Just before and just after shearing the stock is moving between the shearing tools more slowly than normally when everything is idle save the stock-feed. Also the rate of rotation of the rolls is constant at all times and the roll-stand travels away from the shear at the same rate (at the instant of shearing) at which the stock previously has been approaching the shear, this rate being governed by the constant rate of rotation of the rolls and the leftward rate of the roll-stand by clutch N and cams 50. 30 As the roll-stand moves away from the shear, the feed rolls 10-13 no longer move the stock closer to the shear at the same rate as normally, not only because the stock is gripped by 62' in a position of rest, but because the rolls are being 35 carried bodily back away from the shear by the roll-stand moving leftward along the length of the stock just as fast as the stock is issuing from the rolls so that the rolls actually roll back over the fixed stock, idly so far as concerns moving 40 closer to the shear but actively in the sense that they continue their function of a stock-straightening as they move the stock thru and beyond the roll-stand. 45 The action of the rolls 10-13 normally (that is, 105 when clutch N is disengaged which is most of the time) involves exclusively rectilinear lengthwise feeding movement of the long metal or other long longitudinally rigid stock. While such movement, so far as the shearing means is concerned, is interrupted during the instant of shearing, yet it continues all the time with respect to the roll-stand. Normally the action of rolls 10-13 is one of moving the stock toward the shears. But while the shears are being operated by clutch N the latter moves the roll-stand leftward away from the shears; and during the time the shears are moving, and the movement of the stock toward them is respectively slowed down and stopped or even reversed by cams 50, the roll-stand and the rolls in practical effect are being fed leftwardly away from the shears and along the length of the stock, the rolls therefore then continuing their action of ironing out the coil-curvature metal set from the stock. The essence of the operation is this continuous action of stock-straightening during the movements of the shearing tool 63, the timing of the shearing-cut to the instant when the receding movement of the roll-stand is at a rate which causes the stock to be stationary relative to the shear at the instant of shearing, being provided for by the common driver of both the roll-stand and tool 63 by means of the clutch N and fly-wheel gear 44 under the control of the mechanism for determining the length of stock fed beyond the shears up to the instant of shearing. The rearward motion of the roll-stand is however limited to the interval of time including the instant of shearing when the movement of the stock rightwardly beyond the shear is to be prevented, i. e., when shear blade 63 during its shearing cooperation with blade 66 is interposed in the path of the stock and while the latter is gripped to hold it in place in its stationary position for the operation of the shear-blades. As thus far described no time is saved, altho the stock is being continuously straightened in the roll-stand at all times, so that as soon as the shearing operation has been completed and the stock released from

the grippers for resumption of movement by the rolls between the shearing-tools, then the roll-stand, the rolls and the stock all are moved forward toward the shear and the stock is fed between the two shear-blades, the stock being moved rightwardly by two actions (1) the rightward movement of the roll-stand (as by weight 100, clutch N having been disengaged when no longer needed for blade 63) and (2) the normal, continuous, uniform action of rolls 10-13, so that the rate of stock-feed now is much greater than if the roll-stand were stationary. This rate is sufficiently high to make up for the stock-moving time lost during the shearing operation by the horizontally fixed shear. Such higher rate is permitted because straightening of part of the stock has been effected during the time of movements of blade 63, so that most of the stock fed between the shearing tools by the rightward movement of the roll-stand already has undergone the forceful operation of removal of coil curvature, so that the rightward return movement of the stock by weight 100 independently of clutch N can be as rapid as desired, unburdened by the labor of curve-straightening, thereby making up for the time lost during shearing. When the roll-stand reaches its normal position of rest at right, the stock-feed between the shear-blades resumes its normal rate, being thereafter governed by the continuation of the uniform rate of rotation of rolls 10-13 alone without further feeding cooperation by the rightward movement of the roll-stand. In the example shown, however, the above higher rate of stock-feed between the idle shear-blades during the rightward return movement of the roll-stand is further increased by the gravity mechanism which moves the roll-stand rightwardly toward the shear at a higher rate than the leftward movement of the roll-stand by the half-heart-shaped cam. This feed-compensating apparatus is particularly useful in machines for straightening and shearing long relatively narrow metal stock whereby the straightening operation is performed without interruption, yet it may be employed in any machine where the feeding rotation of the rolls is continuous and at a uniform rate but wherein the movement of the metal stock continuously in a straight line is interrupted for the purpose of permitting a fabricating operation, whether shearing or otherwise, and whether or not the stock be straightened prior to the fabricating operation; and indeed said apparatus may be employed irrespective of the nature of the material, metal or otherwise, i. e., in any case where the material has greater length than breadth and is of such character that bending it from a straight length to displace it out of a path of straight lengthwise feed, is impracticable or undesirable in respect of its final condition or the nature of the fabricating operation to which it is to be subjected in the machine. And this feeding apparatus and method may be employed with a plurality of fabricating operations simultaneously executed while the feed of the length of material is discontinued temporarily. Although the apparatus has been described as designed particularly to straighten and shear flat stock, such as long sheets, it may be utilized as well for other long relatively narrow stocks, such as metal rods, bars, e.c. which also are substantially rigid lengthwise.

While I have shown and described one mechanical embodiment of the invention, it is to be understood that this is given merely by way of

example, of how the underlying principles may be incorporated in various designs of the machine.

I particularly point out and distinctly claim the part, improvement, or combination which I claim as my invention or discovery, as follows.

1. A machine for shearing off sub-lengths from long substantially rigid metal stock, which includes the shearing means; means from which the stock is supplied to the shearing means; feeding means which is continuously rotatable to feed the stock continuously lengthwise rectilinearly from said supply means on the side thereof toward the shearing means; and feed-time-compensating means which includes a clutch and a mounting for said feeding means which is reciprocable rectilinearly relative to the shearing means, whereby the feeding-time lost in stopping the stock-movement toward the shearing means during the movement of said mounting away from the shearing means, is substantially compensated for by movement of said mounting toward the shearing means during the intervals between successive shearing actions of the shearing means without displacing any portion of the length of the stock from its straight line of feed. 85 90 95 100

2. In a machine wherein a material of greater length than breadth is fed by rotatable means from a supply means to a fabricating means 105 and the stock movement to the fabricating means discontinued during the fabricating operation, the method of obtaining relatively stationary relations of the fabricating means and feeding means in the direction of stock-feed during fabricating operation, without displacing any portion of length of the long stock away from the path of its movement toward the fabricating means, which consists in causing the rotatable feeding means to recede bodily toward the supply 110 means from the fabricating means during the movement of the latter, and continuing the rotation of the feeding means during its said recession, thereby causing continuous feed of the stock from the feeding means during discontinuance of the stock-movement to the fabricating means. 115 120 125

3. In combination, a shaft, means intermittently rotating said shaft, a reciprocable fabricating instrument, and an operating connection 125 between the latter and said shaft and mounted eccentrically of the shaft; means initiating the rotation of the shaft when the fabricating instrument is intermediate its position engaging the stock and its position most remote therefrom, and when the eccentric is substantially at right angles to said operating connection; all whereby the fabricating instrument initially will be moved from its mid-position further away from the stock, and then moved with a hammer blow to the stock from its position most remote therefrom.

4. A metal treating machine comprising associated feeding and shearing devices, means to operate the shearing device and to displace the feeding device, and reversible means for operating the feeding device independently of the shearing device to permit inspection of the metal under treatment.

5. In an apparatus of the character described, the combination of a reciprocable stock-feeding unit comprising a plurality of rolls; gears therefor; an oil-tight housing; operating mechanism for said unit comprising gearing enclosed in said oil-tight housing, said gearing being connected

- to a source of power; and universal jointed wabblers connecting said gearing and the gears for the rolls of the reciprocable unit.
6. A machine for shearing long, relatively narrow metal stock into sub-lengths, which comprises shearing means; feeding-rolls continuously rotatable to feed the stock continuously from out of the rolls and rectilinearly to the shearing means; stock-supply means in alignment with the shearing means and feed-rolls, the latter being located between the shearing means and the supply-means; a support for said rolls which is reciprocable rectilinearly relative to the shearing means; and means intermittently reciprocating said roll-support, said support being movable away from the shearing means rectilinearly to stop the movement of the stock toward the shearing means while permitting continuation of the feeding of the stock from the rolls during the operation of the shearing means, and said support being movable rectilinearly toward the shearing means between successive shearing operations thereof to cooperate in stock feeding with the continuous feeding of the stock by the rolls and thereby substantially make up the feeding-time lost during the operation of the shearing means; means continuously rotating said feed-rolls; and means including a clutch and intermittently operating said roll-support and simultaneously operating said shearing means.
7. A machine for fabricating long, relatively narrow substantially rigid metal stock at successive portions of its length, which comprises fabricating means; positively and continuously rotatable rolls continuously causing feeding movement of the stock relative to the rolls themselves and rectilinearly to the fabricating means; and a support for the rolls which is reciprocable rectilinearly from and to said fabricating means; means intermittently reciprocating said support; said support being movable away from the fabricating means during the operation of the latter whereby during such operation the feed of the stock toward the fabricating means is discontinued but the stock feeding movement is continued relative to said rolls, said support being movable toward the fabricating means between successive shearing operations of the latter and at a higher rate than its movement away from the fabricating means, all whereby during the intervals between the successive reciprocations of the roll-support, the feeding is continued by the rolls, and whereby the more rapid movement of the roll-support toward the fabricating means compensates for the stoppage of stock-movement toward the fabricating means during the operation of the latter.
8. A metal feeding and shearing device comprising, in combination, a rigid shear mechanism; means intermittently operating the shear mechanism; movable feeding means positioned adjacent the shear mechanism; means continuously operating the feeding means at uniform rate to feed the stock thru it; and means intermittently moving the feeding means away from the shear mechanism during the operation of the shear mechanism and feeding means.
9. A machine for shearing long relatively narrow metal stock which is substantially rigid lengthwise into sub-lengths, including shearing means and rotatable pinch-feed rolls engaging opposite sides of the stock; stock-supply means from which the stock is pulled and pushed exclusively rectilinearly to the shearing means; a normally stationary carrier reciprocable to and from the shearing means and carrying said pinch-rolls; mechanism positively rotating said rolls continuously thereby continuously feeding the stock away from the carrier; and mechanism including a clutch and a fly-wheel and intermittently operating said shearing means and simultaneously moving the carrier and its rotating rolls toward the supply means away from the shearing means, said mechanism at the time of shearing moving the carrier toward the supply means at the same rate that the feed-rolls are moving the stock from the carrier in the opposite direction toward the shearing means.
10. A machine for shearing very long relatively narrow metal stock into sub-lengths, including a shearing-tool, mechanism continuously feeding the stock lengthwise in the direction of the shearing tool; normally stationary tool-operating mechanism including an eccentric; a continuously rotating, positively-acting clutch; mechanism intermittently causing the clutch to be connected with said tool-operating mechanism and its eccentric and impart a single revolution to said eccentric; said eccentric in its normal stationary condition extending generally lengthwise of the long stock being fed toward the shearing tool; and said clutch being arranged to rotate in a direction which in starting the movement of the eccentric from rest causes the movement of the shearing tool away from the stock and then reverses the tool toward the stock for shearing, whereby the starting load on the clutch at each intermittent cycle of the shearing tool is substantially spaced in time from the shearing load on the clutch by the action of the tool on the stock
11. A machine for shearing a very long, relatively narrow but thick metal sheet into sub-lengths, including two shearing tools including a blade, mechanism feeding such sheet lengthwise toward said blade, said blade being arranged with its shearing edge inclined transversely of the width of the sheet being fed to it; normally stationary mechanism including an eccentric for operating such shearing blade; said eccentric normally extending generally lengthwise of the long sheet being fed toward said blade; and driving mechanism intermittently causing a single revolution of said eccentric in a direction which first in starting the blade-operating mechanism from rest moves the blade away from the stock thereby preventing addition of a shearing load to the starting load on the driving mechanism, and then reverses the blade toward the sheet for the gradual shearing action by its inclined edge, thereby not only reducing the instantaneous shearing load on the driving mechanism but substantially spacing the entire shearing load in time from the starting load at each recurrent cycle of said normally stationary eccentric.
12. A machine for shearing very long, relatively narrow metal stock into sub-lengths, including a shearing tool, mechanism feeding the stock lengthwise toward the shearing tool; normally stationary mechanism operating said tool including an eccentric which in its normal position of rest extends generally lengthwise of the long stock being fed toward the shearing tool; and driving mechanism intermittently causing a single rotation of said eccentric mechanism in a direction which first in starting the tool-operating mechanism moves the tool away from the metal stock and then reverses the tool toward the stock for shearing, whereby the shearing load on the driving mechanism at each intermittent

operation of the tool is substantially spaced in time from the starting load.

13. A machine for shearing very long, relatively narrow stock substantially rigid lengthwise into sub-lengths, including a shearing tool, pinch-feed rolls for engaging opposite sides of the long stock and feeding it therefrom lengthwise in the direction of the shearing tool; stock-supply means in alignment with said shearing tool and feed-rolls, the latter located between the supply means and the shearing tool and pulling the stock from the supply means and pushing it to the shearing tool while maintaining the stock in substantially rectilinear condition on both sides of the shearing tool; mechanism including an eccentric for operating the shearing tool; mechanism continuously rotating said feed-rolls at a uniform rate; mechanism including braking means, a clutch and a fly-wheel intermittently causing single complete revolutions of said eccentric; a horizontally extending support for the stock fed beyond the shearing tool and sheared off thereby as a straight sub-length of stock; and mechanism cooperating with said eccentric and pinch-feed rolls and maintaining a uniform relation of the stock and tool in the direction of rectilinear stock-feed during the time of engagement of the tool with the stock, thereby preventing the substantially rigid, rectilinearly fed stock from being moved relative to the proper position of said movable shearing tool during the shearing operation.

14. A machine for shearing very long, relatively narrow metal stock into sub-lengths, including a normally stationary shearing-tool movable to and from the stock, pinch-feed rolls for engaging opposite sides of said long stock and feeding it lengthwise therefrom in the direction of said shearing tool; mechanism including an eccentric for moving the shearing tool to and from the stock; mechanism continuously rotating said feed-rolls; means intermittently imparting a shearing cycle to said tool-moving mechanism, eccentric and tool, said eccentric in its state of rest extending in the general direction of the length of the stock being fed by said rolls; and mechanism cooperating with said eccentric and feed-rolls and maintaining a uniform relation of the stock and shearing tool in the direction of stock-feed during the time of engagement of the tool with the stock.

15. A machine for shearing into sub-lengths very long, relatively narrow metal stock of a thickness causing substantial rigidity lengthwise, said mechanism including two normally stationary shearing tools at least one of which is movable toward the stock, rolls for engaging opposite sides of the long stock and feeding it lengthwise therefrom exclusively rectilinearly toward, between and beyond the shearing tools; at a general rate synchronized with the operation of the shearing means; normally stationary mechanism including an eccentric operating the shearing mechanism a shaft carrying said eccentric; mechanism continuously rotating said feed-rolls at a uniform rate; a continuously rotating positively acting clutch mounted on said shaft with said eccentric; a fly-wheel cooperating with the continuously rotating element of the clutch; mechanism intermittently connecting said clutch and fly-wheel with said shaft and eccentric mechanism during a single rotation of the clutch and eccentric; and mechanism cooperating with said tool-moving mechanism and feed-rolls and maintaining a uniform relation of

the stock and shearing means in the direction of rectilinear stock-feed during the time of engagement of the shearing means with the stock, thereby preventing the substantially rigid rectilinearly fed stock from being moved relative to the proper position of said movable shearing tool during the shearing operation.

16. A machine for shearing very long, relatively narrow metal stock into sub-lengths, including a normally stationary shearing tool movable toward the stock, pinch-feed rolls for engaging opposite sides of the long stock and feeding it lengthwise therefrom in the direction of the shearing tool; normally stationary mechanism including an eccentric for moving the shearing tool to and from the stock; a shaft for said eccentric; mechanism continuously rotating said feed-rolls; a continuously rotating, positively-acting clutch mounted on said shaft with said eccentric; said eccentric in its state of rest extending in the general direction of the length of the stock being fed by said rolls; means intermittently connecting said clutch with said eccentric for a single revolution of the shaft and the eccentric; and mechanism cooperating with said eccentric and feed-rolls and maintaining a uniform relation of the stock and shearing tool in the direction of rectilinear stock-feed during the time of engagement of the tool with the stock.

17. A machine for shearing very long, relatively narrow metal stock into sub-lengths, including a normally stationary shearing tool movable toward the stock, pinch-feed rolls for engaging opposite sides of the long stock and feeding it lengthwise therefrom in the direction of the shearing tool; normally stationary mechanism including an eccentric for moving the shearing tool to and from the stock; a shaft for said eccentric; mechanism continuously rotating said feed-rolls; a fly-wheel and a positively acting clutch mounted on said shaft with said eccentric; driving means continuously rotating said clutch and fly-wheel; said eccentric in its normal state of rest extending in the general direction of the length of the stock being fed by said rolls; means intermittently connecting said fly-wheel and clutch with said eccentric for a single revolution of said shaft; and mechanism cooperating with the eccentric and feed-rolls and maintaining a uniform relation of the stock and shearing tool in the direction of stock feed during the time of engagement of the tool with the stock.

18. A machine for shearing into sub-lengths very long and relatively narrow metal stock having a thickness causing substantial rigidity lengthwise, which includes two cooperating shearing tools for opposite sides of the stock and only one of which is movable to and from the stock, pinch-feed rolls for engaging opposite sides of the stock and feeding it lengthwise therefrom exclusively rectilinearly toward, between and beyond the shearing tools; mechanism continuously rotating said feed-rolls at a uniform rate; a tool carrier on which is mounted the tool which is movable to and from the stock; mechanism intermittently operating said carrier and tool including an eccentric and a member embracing said eccentric and connected to said tool-carrier adjustably for different extents of tool-movement to and from the stock; and mechanism cooperating with said eccentric and roll-rotating mechanism and maintaining a uniform relation of the stock and shearing means in the direction of rectilinear stock-feed during the engagement of said movable tool with the stock.

19. A machine of the general character described, for fabricating very long relatively narrow stock of substantial rigidity lengthwise including a fabricating tool, continuously operating feeding mechanism feeding the stock exclusively rectilinearly to and beyond the fabricating mechanism, said machine normally and stationary tool-operating mechanism, a continuously-rotating positively-acting clutch intermittently actuating the tool-operating mechanism; braking means for the tool-operating mechanism; means causing the operation of said braking means prior to the end of the cycle of the tool-operating mechanism whereby the movement of the latter is checked substantially instantly at the end of said cycle; and mechanism cooperating with said tool-operating mechanism and stock-feeding mechanism and maintaining a uniform relation of the stock and tool in the direction of rectilinear stock-feed during their engagement with one another thereby preventing the continuous operation of the feeding means from moving the substantially rigid, rectilinearly fed stock relative to the working portion of said tool during the fabricating operation. 80
20. A machine of substantially the character described for fabricating very long relatively narrow stock of substantial rigidity lengthwise, said machine, including a fabricating tool, continuously operating feeding mechanism, feeding the stock exclusively rectilinearly to and beyond said tool, normally stationary tool-operating mechanism, including an eccentric; mechanism intermittently imparting a single revolution to said eccentric; braking mechanism; means causing the operation of said braking mechanism to said tool-operating mechanism prior to the end of eccentric revolution; and mechanism maintaining a uniform relation of the stock and tool in the direction of rectilinear stock-feed during the engagement of the tool with the stock thereby preventing the continuously operated feeding mechanism from causing the substantially rigid, rectilinearly fed stock to move relative to the proper position of said tool during the shearing operation. 85
21. A machine of substantially the character described for fabricating very long relatively narrow stock of substantial rigidity lengthwise, said machine, including a fabricating tool, continuously operating mechanism feeding the stock horizontally lengthwise and exclusively rectilinearly to and beyond said tool; intermittently-acting tool-operating mechanism including a horizontal shaft bearing an eccentric which in its normal position of rest extends generally horizontally and lengthwise of the stock being fed; mechanism maintaining a uniform relation of the stock and shearing tool in the direction of stock-feed during the engagement of the tool with the stock; braking mechanism; and means holding said braking means applied to said tool-operating mechanism while said eccentric is moving against gravity to its normal position of rest. 90
22. A machine of substantially the character described which includes a fabricating tool, continuously operating mechanism feeding the stock horizontally lengthwise; intermittently-acting tool-operating mechanism including a horizontal shaft bearing an eccentric which in its normal position of rest extends generally horizontally and lengthwise of the stock being fed; mechanism maintaining a uniform relation of the stock and shearing tool in the direction of stock-feed during the engagement of the tool with the stock; and mechanism holding said tool-operating mechanism and horizontal eccentric against gravity in their normal position of rest. 95
23. A machine of substantially the character described for shearing into sub-lengths, very long relatively narrow longitudinally rigid stock, said machine including two normally stationary shearing tools of which at least one is movable to and from a side of the stock, bodily movable pinch-feed rolls for engagement with opposite sides of the stock and feeding it lengthwise therefrom exclusively rectilinearly to and beyond said tool; stock-supply means aligned with said rolls and tool and from which the latter pull the stock rectilinearly; intermittently-acting mechanism operating the shearing means; continuously-operating mechanism coordinated with said intermittently-acting mechanism; jointed transmission mechanism rotating said bodily-movable rolls at a uniform rate and extending between said continuously-operating mechanism and said rolls; and mechanism cooperating with said roll-operating mechanism and said shear-operating mechanism and maintaining a uniform relation between the stock and said movable tool during their engagement with one another, whereby the stock is moved exclusively rectilinearly by the continuously rotating rolls but does not move relative to the proper position of said movable tool during the shearing operation; a driver for said stock-feeding mechanism; and manually controlled means for reversing at will the direction of operation of said feeding mechanism. 100
24. A machine for shearing into sub-lengths very long and relatively narrow stock having substantial rigidity longitudinally, said machine including two normally stationary shearing tools of which at least one is movable in an excursion to and from the stock, pinch-feed rolls continuously acting to feed the stock lengthwise therefrom exclusively rectilinearly to and beyond said shearing means; mechanism intermittently operating the shearing tool; mechanism driving said tool-operating mechanism and including a continuously-rotating positively acting clutch; mechanism cooperating with said tool operating and stock-operating mechanisms and maintaining a uniform relation of the tool and rectilinearly moving stock lengthwise of the stock during the time of engagement of the stock and tool with one another, thereby preventing the continuously rotating rolls from moving the longitudinally rigid, rectilinearly fed stock relative to the proper position of said movable tool during the shearing operation; and mechanism regulating the times of successive operations of the tool-operating mechanism by the clutch, said regulating mechanism including a variable speed transmission; arranged for continuous operation at a rate coordinated with the rate of effective stock-feed. 110
25. A machine for fabricating very long and relatively narrow stock at portions spaced apart lengthwise substantially the same distance, said stock being substantially rigid longitudinally, said machine including mechanism feeding the stock lengthwise exclusively rectilinearly, a fabricating tool movable in an excursion to and from the stock but normally stationary; normally stationary mechanism intermittently operating and causing successive fabricating excursions of said tool; mechanism continuously operating said stock-feeding mechanism; mechanism cooperating with said mechanisms which operate said tool and feeding mechanism respectively and maintaining a uniform relation of the stock and tool to one another lengthwise of the stock during their 120

- 150

- engagement with one another, thereby preventing the continuously operating stock feeding mechanism from moving the longitudinally rigid, rectilinearly fed stock relative to the proper position of said fabricating tool during the fabricating operation, and mechanism continuously operating at a rate coordinated with the effective stock-feed and controlling the times of successive excursions of the fabricating tool by said intermittently operating mechanism to cause fabricating operations of the tool on the stock at portions of the length thereof which are spaced substantially equal distances apart. 5
26. A machine for shearing very long and relatively narrow stock into uniform sub-lengths, said stock being substantially rigid longitudinally said machine including a normally stationary shearing tool movable in shearing excursions to and from the stock, mechanism feeding the stock lengthwise exclusively rectilinearly to and beyond said tool; normally stationary mechanism intermittently operating said tool; mechanism continuously operating said stock-feeding mechanism; mechanism cooperating with said mechanisms respectively operating the tool and the feeding mechanism and maintaining a uniform relation of the stock and tool to one another lengthwise of the stock during their engagement with one another, thereby preventing the continuously operating stock-feeding mechanism from moving the longitudinally rigid, rectilinearly fed stock relative to the proper position of said shearing tool during the fabricating operation; a continuously-rotating, positively-acting clutch; 30 mechanism continuously operating at a rate coordinated with the rectilinear movement of the stock and causing initiations of intermittent connections of said clutch with said tool-operating mechanism at times causing shearing of the stock into substantially equal sub-lengths; and mechanism causing disconnection of said clutch before it has moved the shearing tool in excess of a single excursion. 35
27. A machine for shearing very long and relatively narrow longitudinally rigid stock into sub-lengths, including a shearing tool, a plurality of rolls for engagement with opposite sides of the stock for feeding it to the shearing tool; mechanism continuously and positively rotating said feed-rolls moving the stock exclusively rectilinearly to and beyond the tool; mechanism including a positive-acting clutch intermittently operating said shearing tool during the continuous operation of said rolls; mechanism maintaining a uniform relation of the tool and stock to one another during their engagement with one another; and manually controlled means for reversing at will the direction of operation of said feed-roll rotating mechanism. 50
28. A machine for shearing very long and relatively narrow longitudinally rigid stock into sub-lengths, including a shearing tool; a plurality of rolls for engagement with opposite sides of the stock for feeding it to the shearing tool; mechanism continuously and positively rotating said rolls moving the stock exclusively rectilinearly to and beyond the shearing tool; mechanism including a positive-clutch and intermittently operating said shearing tool during the continuous operation of said rolls; mechanism maintaining a uniform relation of the tool and stock to one another during their engagement with one another, thereby preventing the continuously operating stock-feeding mechanism from moving the longitudinally rigid, rectilinearly fed stock relative to the proper position of said shearing tool during the shearing operation; and manually operable mechanism reversing the direction of rotation of said roll-rotating mechanism during the continuously operating of said other moving parts of the machine. 55
29. A machine for shearing very long and relatively narrow longitudinally rigid stock into uniform sub-lengths, including the following elements substantially as described:— a shearing tool; continuously operating mechanism feeding the long stock lengthwise, moving the stock exclusively rectilinearly to and beyond said tool; normally stationary tool-operating mechanism including a radially extending member the outer portion of which is movable in a circle and to which the tool is connected; mechanism maintaining a uniform relation between the stock and tool lengthwise of the stock during their engagement with one another, thereby preventing the continuously operating stock-feeding mechanism from moving the longitudinally rigid, rectilinearly fed stock relative to the proper position of said shearing tool during the shearing operation; a continuously-rotating positively-acting clutch arranged to drive the tool-operating mechanism and cause a single revolution of said radially extending member; mechanism normally holding the clutch out of driving relation with the tool-operating mechanism; means intermittently initiating inoperativeness of said holding mechanism at times equally spaced apart for equal lengths of stock-feed; a common driver for all said movable parts of the machine; and manually controlled means for reversing at will the direction of operation of stock-feeding mechanism which normally feeds the stock toward the shearing tool. 60
30. A machine for shearing very long and relatively narrow longitudinally rigid stock into sub-lengths, including a shearing tool, mechanism including a positive-acting clutch and intermittently operating the shearing tool moving it thru an excursion to and from the stock; a plurality of rolls for engagement with opposite sides of the stock to feed it to the shearing tool; mechanism continuously and positively rotating said rolls, moving the stock exclusively rectilinearly to and beyond said shearing tool; the rolls and said driving mechanism being arranged for roll-adjustment to various thicknesses of stock; mechanism maintaining a uniform relation between the stock and shearing tool lengthwise of the stock during their engagement with one another, thereby preventing the continuously operating stock-feeding mechanism from moving the longitudinally rigid, rectilinearly fed stock relative to the proper position of said shearing tool during the shearing operation; means intermittently initiating operation of the tool-operating mechanism at times spaced apart for equal lengths of stock fed beyond the shearing tool; and manually controlled means for causing at will the reversal of said normal direction of operation of the mechanism for rotating the feed-rolls. 65
31. A machine for shearing very long and relatively narrow stock into sub-lengths, including a shearing tool, pinch-rolls feeding the stock; mechanism continuously and positively rotating said rolls; normally stationary driving mechanism including a positive acting clutch intermittently operating the shearing tool moving it thru an excursion to and from the stock; mechanism maintaining a uniform relation to the stock and tool lengthwise of the stock during their engagement with one another; continuously operating 70

- mechanism normally holding said driving mechanism out of driving relation with the tool; an electromagnetic means controlling said holding mechanism; a common driving source for all said 5 movable parts; manually operable mechanism stopping the operation of said roll-rotating mechanism at will during the continued operation of said other moving parts; a switch in the circuit of said electromagnetic means; manually operable mechanism reversing the direction of operation of said roll-driving mechanism at will; and mechanism controlling the time of operation of said electromagnetic means in accord with the feed of the stock.
- 15 32. A machine for shearing very long and relatively narrow longitudinally rigid stock into sub-lengths, including a shearing tool, pinch-rolls feeding the stock, mechanism continuously and positively rotating said rolls moving the stock 20 exclusively rectilinearly to and beyond the shearing tool; normally stationary mechanism including a positive-acting clutch and intermittently operating the shearing tool moving it thru an excursion to and from the stock; mechanism 25 maintaining a uniform relation of the stock and tool lengthwise of the stock during their engagement with one another, thereby preventing the continuously operated rolls from moving the longitudinally rigid, rectilinearly fed stock relative 30 to the proper position of the shearing tool during the shearing operation; continuously driving mechanism including a positive-acting clutch arranged to impart intermittent excursions to the shearing tool; mechanism normally holding said 35 driving mechanism out of driving relation with the tool; electro-magnetic means controlling said holding mechanism; a switch in the circuit of said electro-magnetic means and controlling the connection of the driving means in operating relation with the shearing tool; and manually controlled means for causing at will the reversal of the direction of operation of the mechanism for 40 rotating the feed-rolls.
33. A fabricating machine for long relatively narrow longitudinally rigid metal stock, which includes feeding means consisting of feed-rolls pinching the stock between them in combination with means continuously rotating them and means reciprocating them in the line of stock-feed while they are being rotated; a normally stationary fabricating tool and a carrier therefore, in combination with means intermittently moving the carrier and tool in a cycle to and from the line of stock-feed by said pinch-rolls; stock 45 supply means alined with the feed rolls and fabricating tool and from which the former moves the stock exclusively rectilinearly, pulling the stock from said supply means and pushing it to and beyond the fabricating tool; and means also carried by said tool-carrier and movable toward the stock with the fabricating tool and having clamping engagement with the stock during the fabricating operation of said tool on the stock when the feed-rolls are being moved bodily toward the 50 supply means at the same rate that the stock is moving relatively from the feed-stock.
34. In a machine for fabricating long narrow metal stock, the combination with feeding-means, of mechanism driving the feeding means in either of two directions; a fabricating tool movable in cycles to and from the line of stock-feed; a manually-operable clutch controlling the operation of said tool; a reversing clutch controlling the driving mechanism for the feeding means; and man- 55 ually operable means controlling said reversing clutch.
35. In a machine for fabricating long narrow longitudinally rigid metal stock at successive portions of its length, the combination with continuously operated roll mechanism relatively feeding the stock lengthwise, and exclusively rectilinearly to and beyond the fabricating means; of fabricating means intermittently movable in cycles to and from the path of stock-feed; said feeding mechanism including a roll-stand slidingly reciprocable rectilinearly in the direction of stock-feed and the feed-rolls being rotatably mounted in the roll-stand; stock-supply means alined with the feed-rolls and fabricating mechanism and from which the rolls move the stock exclusively rectilinearly pulling it from said supply-means and pushing it to and beyond the fabricating means; a main driver; and power transmissions all operated by said main driver and connected respectively to said fabricating means said roll-stand and said feed-rolls; the connections between the main driver and the roll-stand and rolls respectively including an intermittently operated positive acting clutch.
36. In a machine of the general character described, for shearing long relatively narrow metal stock into equal sub-lengths, the combination with rolls moving the long stock rectilinearly lengthwise, of supply means from which the stock is moved by said rolls, and shearing means located in line with said supply means and feed-rolls; means continuously rotating said feed rolls at a uniform rate; a roll-stand carrying said feed-rolls and slidably mounted for rectilinear reciprocation in line with the supply means and shearing means; said shearing means including two tools of which one is movable to and from and across the line of rectilinear stock-feed from the supply means to the shearing means; means operating said movable shearing tool; means operating said roll-stand; a normally disengaged clutch connected to both said operating means; said elements being arranged for movement of the roll-stand away from the shearing means at the time after clutch engagement when the movable shearing tool is being moved to shear the stock; means controlling the intermittent operations of said clutch; and means continuously operating the driving element of the clutch at a rate in time-relation coordinated with the rate of continuous rotation of the feed-rolls; all whereby at the instant of shearing the roll-stand is moved away from the shearing means at the same rate as the stock is emerging from the feed-rolls carried by the roll-stand.
37. A machine for shearing long substantially rigid metal stock into uniform sub-lengths, which includes a base, shearing means and a roll-support mounted for sliding reciprocation on the base, one element of the shearing means being rigidly related with the base and the cooperating element being movable along the other across the path of longitudinal stock-movement; a plurality of rolls carried by the support; means including a clutch and a half-heart-shaped cam for sliding the roll-support intermittently away from the shearing means and simultaneously operating the movable shearing tool, said mechanism including a shear-gate and an eccentric; mechanism continuously rotating said rolls; means sliding the roll-support intermittently back to its normal condition of rest, said mechanism including a gravity-actuated counter-balancing weight and a common driver for said respective means for rotating

said rolls, operating said clutch-including means and intermittently raising said counter-weight.

38. In a machine for treating long substantially rigid metal stock, which includes a fabricating means operating intermittently on portions of the long stock at desired distances from one another, the means for increasing the output of the machine in a given time which includes rotatable stock-feeding means continuously feeding the stock rectilinearly in the direction toward the fabricating means, but which is intermittently reciprocatable rectilinearly from and back toward the fabricating means; means operating the fabricating means at times when the movement of the stock toward it is prevented by the bodily movement of the rotatable feeding means away from the fabricating means; and means including a clutch and intermittently operating said fabricating means and simultaneously bodily moving the rotating feeding means rectilinearly away from the fabricating means.

39. A machine for shearing long substantially rigid metal stock into uniform sub-lengths, which includes a base, shearing mechanism supported on the base; a support also mounted on the base for rectilinear sliding movement from and toward the shearing mechanism; feed-rolls carried by said support and feeding the stock rectilinearly to and beyond the shearing mechanism; means continuously rotating said feed-rolls; and means including a clutch and a half-heart shaped cam intermittently sliding said roll-support away from the shearing mechanism and simultaneously operating said shearing mechanism.

35. 40. In a machine for shearing long substantially rigid metal stock into successive sub-lengths, the combination with a base, of shearing means mounted on the base and including a tool movable across the stock-path; a support mounted on the base for rectilinear sliding reciprocation from and toward the shearing mechanism; stock-feeding rolls carried by said support and feeding the stock rectilinearly to the shearing means; a gate for said tool and a resilient metal-holding device mounted on the gate; means continuously rotating said feed-rolls; and means including a clutch and a half-heart-shaped cam and intermittently sliding said roll-support away from the shearing mechanism and simultaneously operating said shear-gate.

41. In a machine of the general character described for treating long substantially rigid metal stock, the combination with shearing means, of continuously rotatable stock-feeding means feeding the stock rectilinearly to the fabricating means; means including a clutch and intermittently moving the continuously rotating feeding means bodily away from the shearing means and simultaneously operating the shearing means; and means positively gripping the stock and holding it in its stationary position notwithstanding the continuous rotation of the stock-feeding means and during the time of bodily movement of the feeding means away from the shearing means; said clutch including means moving said feeding means bodily at the same rate as that of the emergence of the stock from the feeding means, and intermittently operating said stock-gripping means to hold the stock in its resulting stationary relation to the shearing means in the direction of the rectilinear feed of the stock.

42. A machine of the class described, for fabricating long substantially rigid metal stock, and including a base, fabricating means; a support slideable on the base rectilinearly from and toward

the fabricating means; stock-feeding rolls carried by said support and feeding the stock rectilinearly to the fabricating means; means including a fly-wheel and clutch and intermittently sliding said roll-support from the fabricating means and simultaneously operating the fabricating means; and transmission means continuously rotating the feed-rolls and yieldable to said intermittent sliding of the roll-support.

43. A machine for shearing long relatively narrow and substantially rigid metal stock successively into sub-lengths, and including stock-feeding means rectilinearly reciprocable along the stock including rotatable feed-rolls; shearing mechanism mounted in the path of longitudinal stock-feed; said feed-rolls feeding the stock rectilinearly to the shearing mechanism; driving means; a transmission from said driving means continuously rotating said feed-rolls; and a transmission from said driving means including a clutch and fly-wheel and intermittently moving said stock-feeding means rectilinearly away from the shearing mechanism and simultaneously operating the shearing mechanism for shearing the stock at the instant when the feeding means is moving away from the shearing mechanism at the same rate that the stock is emerging from the feed-rolls.

44. A machine for fabricating long, relatively narrow and substantially rigid metal stock successively at uniformly speed portions of its length, and including fabricating means and rotatable stock-feeding rolls feeding the stock rectilinearly to the fabricating means; a normally stationary roll-carrier reciprocable rectilinearly along the rigid stock from and to the fabricating means; mechanism positively rotating said rolls continuously; and mechanism including a clutch and fly-wheel and intermittently moving said roll-carrier away from the fabricating means and simultaneously operating the latter for shearing at the time when the continuously rotated rolls are being carried bodily away from the fabricating means at the same rate that the stock is emerging from the rolls.

45. In a machine for fabricating long substantially rigid metal stock at uniformly spaced portions of its length, the combination with fabricating means including an element movable toward the stock, of feeding means continuously rotatable and feeding the stock rectilinearly to the fabricating means; a sliding support for the rotatable feeding means, said support being reciprocable from and to the fabricating means along the length of the rectilinearly fed rigid stock; means continuously rotating the feeding means; means including a clutch and intermittently sliding said support away from the fabricating means and simultaneously effecting fabricating operation of said movable element of the fabricating means; and means which after disconnection of said clutch slides said support back toward the fabricating means at a rate higher than the movement of the support away from the fabricating means by the clutch.

46. In a machine for treating long substantially rigid metal stock, the combination with a normally stationary fabricating element movable toward the stock, of rotatable feeding rolls feeding the stock rectilinearly to the fabricating element; means continuously rotating said rolls; and feed-time-compensating means including a support for said rotatable feeding means, said support being slideable from and back toward the fabricating means along the rectilinearly fed

- rigid stock, means including a clutch and intermittently moving said support away from the fabricating element and simultaneously imparting fabricating movement to said element, and 5 means intermittently sliding said support back toward the fabricating element.
47. In a machine for shearing long substantially rigid metal stock into uniform sub-lengths, the combination with shearing means including a 10 tool reciprocable across the stock, of means feeding the stock rectilinearly to and beyond the shearing means and including rolls continuously rotated in directions for feeding the stock in said direction; a support in which said rolls are rotatably mounted, said support being mounted for intermittent sliding rectilinear reciprocation from and to the shearing means rectilinearly along the path of rectilinear feed of the rigid stock; driving means; a transmission between the driving 15 means and the feed-rolls continuously rotating them and including universally jointed wabblers accommodating themselves to the said reciprocation of the roll-support; and a transmission between said driving means and said roll-support 20 and shearing tool respectively and including a bull-gear continuously operated by said driving means and means including a normally idle shaft on which said bull-gear is mounted and intermittently reciprocating the roll-support and shearing tool for shearing operation when the said tool and the stock are relatively stationary in the direction of stock-feed and when a predetermined sub-length of stock has been fed to the path of movement of the tool across the stock, said intermittent means including also wedging rolls for connection between said bull-gear and its shaft; means controlled by the operation of the driving 25 means which rotates the feed rolls for connecting said wedging rolls between said gear and shaft; means disconnecting said rolls from said gear; means braking said shaft upon said roll-disconnection; all whereby said feed-roll support is moved away from the shearing means and the movable shearing tool is reciprocated back and forth across the path of stock-feed; and means independent of said driving means and connecting rolls and moving said roll-support back toward the shearing means at a higher rate than it is moved in the opposite direction.
48. A machine for shearing long substantially rigid metal stock into uniform sub-lengths, including a shearing tool movable across the stock, mechanism including rotatable rolls feeding such stock rectilinearly lengthwise to and beyond said tool; a main driver; a transmission from the driver and continuously rotating said rolls; supports for said tool and rolls respectively and means for intermittently causing relatively stationary relations of said stock and tool support in the path of stock-feed, and simultaneously moving the tool across the stock for shearing at a time when the tool and the feeding stock are relatively stationary in the path of stock-feed; said intermittent means including an eccentric device; a transmission between said main driver and said intermittent means and eccentric device and including a bull-gear, and also including wedging driving rolls for intermittent connection between the bull-gear and said intermittent means; electromagnetic means controlling the movement of said driving rolls to their connecting positions; means controlled by the operation of said main driver and itself controlling the operation of said electromagnetic means; means intermittently moving said driving-rolls from their 50 connecting positions; and braking means stopping said intermittent means upon the disconnection of said driving rolls from the bull-gear.
49. A machine for shearing long substantially rigid metal stock into uniform sub-lengths, including a shearing tool movable across the stock, rolls feeding such stock rectilinearly lengthwise to and beyond said tool; a main driver; a power transmission from the driver and continuously rotating said rolls; supports for said tool and rolls respectively and means including an eccentric and intermittently causing relatively stationary relations of said stock and tool support in the path of stock-feed and simultaneously moving the tool back and forth across the stock for shearing and removal of the tool from the path of the stock, said movements of the tool across the stock-path being effected at a time when the stock and the tool are relatively stationary in the path of stock-feed; a transmission between the driver and said intermittent means and including wedging driving rolls for intermittently connecting the driver to said intermittent means; means controlled by the operation of the driver itself and causing such locking of the driver to the intermittent means; means intermittently causing unlocking of said elements; and braking means stopping said intermittent means upon said unlocking.
50. A machine for shearing into uniform sub-lengths, very long relatively narrow metal stock of a thickness causing substantial rigidity lengthwise, said machine including two normally stationary cooperating shearing tools at least one of which is movable across the stock for shearing; rolls for engaging opposite sides of the long stock and feeding it lengthwise rectilinearly between and beyond the shearing tools in their normal stationary positions; supports on which said rolls and tools are mounted and locating the tools normally on opposite sides of the rectilinear path of the stock by the rolls; mechanism continuously rotating said rolls; intermittent operating mechanism causing relatively stationary relations of said stock and tool support in the path of the rectilinear stock-feed by said rolls and including an eccentric and causing movement of said tool back and forth across the stock-path when the stock and the tools are relatively stationary in the path of stock-feed; a main driver; a transmission between the driver and said intermittent operating means and including wedging driving rolls for intermittently connecting the driver to said eccentric; means controlled by the operation of the driver itself and causing such locking of the driver to the intermittent means; means intermittently effecting unlocking of said elements after said movable tool has been moved thereby from out of the path of movement of the stock by said feed-rolls; and braking means stopping said intermittent means and eccentric and holding said movable tool out of the stock-path in its normally stationary position.
51. A machine for shearing long substantially rigid metal stock into uniform sub-lengths, including a shearing tool movable across the stock, rolls feeding such stock rectilinearly lengthwise to and beyond said tool; a main driver; a power transmission from the driver and continuously rotating said rolls; supports for said tool and rolls respectively and means including an eccentric and intermittently causing relatively stationary relations of said stock and tool support in the line of rectilinear stock-feed and simultaneously moving the tool back and forth across

- the stock for shearing and removal of the tool from the stock-path at a time when the stock and tool are relatively stationary in the path of stock-feed; a transmission between the driver and said intermittent means and including wedging driving rolls for intermittently connecting the driver to said intermittent means; electromagnetic means controlling the movement of said driving rolls to their connecting positions; means controlled by the operation of said main driver and itself controlling the operation of said electromagnetic means; means moving said driving rolls from their connecting position after they have moved said tool out of the path of stock-feed; and braking means stopping said intermittent means and holding said tool out of the stock path after said disconnecting operation by the driver. 50
52. A machine for shearing long substantially rigid metal stock into uniform sub-lengths, including a shearing tool movable across the stock, rolls feeding such stock rectilinearly lengthwise into shearing position to and beyond said tool; a main driver; power connections from the driver to the feeding rolls and tool including a continuously rotating fly-wheel element acting on both said rolls and tool and including connections continuously rotating the rolls and including supports respectively for the rolls and tool, and connections intermittently causing relatively stationary relations of said stock and tool support in the path of rectilinear stock-feed by the rolls, said power connections including also wedge-rolls for intermittently effecting said tool-operations by making driving connection with said driver; means controlled by the operation of the driver and controlling the time of movement of said driving-rolls to their connecting positions relative to the stock-feed by the feeding rolls; means intermittently moving said driving-rolls from their power-connecting positions; and braking means stopping said intermittent means upon the disconnection of said wedging rolls from the driver. 55
53. A machine for shearing into uniform sub-lengths, very long and relatively narrow and substantially rigid metal stock, which includes two normally stationary shearing tools of which at least one is movable back and forth across the stock-path, pinch-rolls for engaging opposite sides of the stock and feeding it lengthwise rectilinearly to, between and beyond the shearing tools into shearing position; stock-clamping means; a main driver; power connections from the driver to the pinch rolls, said movable shearing tool and stock-clamping means and including a continuously rotating fly-wheel element acting on both said tool and the pinch-rolls and including connections continuously rotating the rolls and including supports for said rolls and movable tool, and connections intermittently causing relatively stationary relations of said stock and tool support in the path of rectilinear stock-feed by the rolls and intermittently operating said stock-clamping means to clamp the stock; said power-connection to the movable tool and stock-clamping means including also wedge-rolls for intermittently driving them by making connection between them and said driver; means controlled by the operation of the driver in coordination with the rate of stock-feed by the pinch-rolls and controlling the times of movement of said driving-rolls to their connecting positions; means intermittently moving said driving-rolls from their power-connecting positions after 75
- said tool has been moved out of the stock-path and said clamping means has been moved out of clamping engagement with the stock; and braking means stopping the operation of the intermittently operated elements and holding the shearing tools and clamping means in their normally non-operating positions. 80
54. A machine for shearing very long and relatively narrow substantially rigid stock into uniform sub-lengths, including a normally stationary shearing tool movable in intermittent shearing excursions back and forth across the stock; continuously operable mechanism rectilinearly feeding the stock lengthwise to and beyond said tool; means continuously operating said feeding mechanism; a driver; supports for said feeding mechanism and shearing tool; intermittently operating mechanism causing relatively stationary relations of said stock and tool support in the path of rectilinear stock-feed and simultaneously moving the tool across the stock for shearing and out of the rectilinear path of stock-feed while the tool and stock are relatively stationary in the direction of rectilinear stock-feed, and all in coordinated time-relations with the stock-feed; a power-transmission between said driver and intermittent means and including driving wedge-rolls for connecting the driver to said tool-operating offset device; means controlled by the operation of the driver and causing such intermittent connection to the driver, said means being adjustable by the operator for predetermination of length of sub-length without any other change of the machine; means controlled by the intermittently moving elements and moving said driving-rolls from their connecting positions; and braking means stopping the intermittently moved elements after the shearing tool has been moved out of the rectilinear stock-path, and holding said tool in its normally stationary position out of the stock-path during feeding of the stock. 90
55. A machine for shearing very long and relatively narrow and substantially rigid metal stock into uniform sub-lengths, including a normally stationary shearing tool movable in intermittent excursions back and forth across the stock; continuously operable mechanism rectilinearly feeding the stock lengthwise to shearing relation with said tool; means continuously operating said feeding mechanism; intermittently operating mechanism causing relatively stationary relations of the stock and tool during shearing and including means operating the tool, all in co-ordinated time-relations with said rectilinear stock-feed by the continuously operated feeding mechanism; a constantly operating driver for said intermittent mechanism; a power transmission between them including wedge-rolls driving said intermittent mechanism; means predetermining production of desired sub-lengths by the above elements as specified, said means being adjustable by the operator; electromagnetic means controlled by said adjustable means, the electromagnetic means controlling the times of movement of said driving-rolls to their power-transmitting positions; means controlled by the operation of said intermittent mechanism and controlling the movement of said driving-rolls from their power transmitting positions; and braking means stopping the intermittent elements after said tool has been moved out of the path of rectilinear stock-feed, and holding the tool in its normally stationary position out of said stock-path. 100
